UNITED STATES PATENT OFFICE.

HENRY LAREW, OF BUTTE, MONTANA.

DESIGN FOR A NUT-LOCK.

SPECIFICATION forming part of Design No. 29,517, dated October 18, 1898.

Application filed September 3, 1898. Serial No. 690,233. Term of patent 7 years.

To all whom it may concern:

Be it known that I, HENRY LAREW, a citizen of the United States, residing at Butte, in the county of Silver Bow and State of Montana, have invented and produced a new and useful Design for a Nut-Lock, of which the following is a specification.

This invention is a new and useful design for a nut-lock, the leading feature being the peculiar shape or configuration thereof.

In the drawings forming a part of this specification, Figure 1 is a perspective view of a lock-nut constructed in accordance with my design, and Fig. 2 is a sectional view thereof.

Referring to the drawings by letters, A indicates the lock-nut, rectangular in shape and having rounded edges B, and upon the top of this rectangular-shaped nut is a circular col-

lar C, having rounded upper edges D, and a vertical boss E is produced upon the side of the collar, said boss having a circular aperture F.

The nut is chamfered upon its lower face, as shown at G.

A lock constructed in accordance with the hereinbefore-described design is useful and fulfills all the objects for which it is designed.

Having thus fully described my invention, what I claim as new, and desire to secure by Letters Patent of the United States, is—

The design for a nut-lock herein shown and described.

HENRY LAREW.
